UNITED STATES PATENT OFFICE.

WILLIAM H. BAKER AND CLARK E. CARTER, OF MONTREAL, QUEBEC, CANADA; SAID CARTER ASSIGNOR TO SAID BAKER.

BOBBIN OR COP FEELER.

1,403,728.

Specification of Letters Patent. Patented Jan. 17, 1922.

Application filed February 5, 1919. Serial No. 275,247.

To all whom it may concern:

Be it known that we, WILLIAM H. BAKER and CLARK E. CARTER, both citizens of the United States, residing at the city of Montreal, in the Province of Quebec and Dominion of Canada, have invented certain new and useful Improvements in Bobbin or Cop Feelers, of which the following is a full, clear, and exact description.

- 10 This invention relates to improvements in feeler mechanism for looms, and more particularly to that class of feeler mechanism adapted to detect an insufficiency of filling on a bobbin or cop in the loom shuttle.
- 15 The object of the invention is to provide a mechanism which will feel the filling at every second pick and when the amount of filling is insufficient will be operated to set in motion a filling replenishing mechanism.
- 20 According to this invention, the front of the shuttle box and the front of the shuttle are apertured for the entrance of the feeler, which is mounted in a suitable position on the loom frame and which controls a trigger
- 25 adapted to connect the weft hammer and the filling replenishing actuating means. When the amount of filling is insufficient, the feeler mechanism receives motion from the lay which places the trigger in operative
- 30 position between the weft hammer and filling replenishing actuating means. The feeler proper comprises two relatively movable parts which are bodily movable together without alteration of their relation. One of
- 35 these parts is adapted to feel the filling and the other to feel the shuttle. As long as there is a sufficiency of filling, no relative movement of the parts occurs, but when there is an insufficiency of filling the shuttle
- 40 feeler is moved by engagement with the shuttle before the filling feeler is engaged and moved by the filling. In this way, relative movement of the feeler parts is produced, which movement is communicated to
- 45 the trigger.

In the drawings which illustrate the invention;—

Fig. 1 is a plan view of the device in position on a loom.

50 Fig. 2 is a front elevation of the feeler.

Fig. 3 is a fragmentary view illustrating the contact of the feeler and filling when there is a sufficiency of filling.

Fig. 4 is a similar view illustrating the operation of the feeler by an insufficiency of filling.

Fig. 5 is a fragmentary plan view showing a modified form of feeler tip for use with cop spikes.

Referring more particularly to the drawings, 11 designates the frame of a loom and 12 the loom lay carrying the shuttle box 13 having an opening 14 in the front wall thereof opposite which the shuttle 15 comes to rest. The weft hammer is designated by 16 the numeral 16 and a shaft for communicating movement to a filling replenishing mechanism is designated 17. A bobbin or cop 18 carrying filling 19 is secured in the shuttle in any suitable manner, for example, by means of spring fingers 20 which grasp the bobbin or cop head. According to this invention, the stem of a bobbin when such is used is provided with a diametrically disposed slot 21 adjacent the head. A slot 22 is provided in the front side wall of the shuttle opposite the bobbin slot and opposite the opening 14 in the front of the shuttle box. This shuttle slot extends far enough toward the point of the shuttle to expose one of the spring fingers 20 carrying the bobbin.

An arm 23 is mounted at one end on the shaft 17 and at the opposite end carries a pivotally mounted trigger 24, the point of which is adapted to engage a single tooth 25 or step 25 of the weft hammer. This trigger is provided with a longitudinally disposed slot 26. The lever 23 may be shaped as shown in order to enable it to pass around the breast beam 26 of the loom, so that the trigger will be readily accessible for adjustment.

The feeler mechanism proper comprises a bracket 27 secured to the loom frame which may of course be replaced by a lug 95 cast on the frame. A lever 28 is pivotally mounted toward one end on the bracket. The long arm of this lever terminates in a feeler finger 29 extending toward the shuttle and positioned to pass through the shuttle box and shuttle openings into engagement with the filling. Adjacent the finger 29 the lever 28 is provided with a pin 30 against which bears one end of a spring 31, the opposite end of which is rigidly secured to 105 the bracket 27. The function of this spring

is to urge the feeler finger toward the shuttle. In order to limit the movement of the lever 28 under influence of the spring 31, a stop 32 is provided on the short arm of the lever in position to engage the bracket 27. At the root of the feeler finger 29 a bell crank lever 33 is pivoted. One arm of this lever is offset, as shown in Figure 2, to bring it into the plane of the finger 29 and terminates in a broad-rounded nose 34 adapted to pass through the shuttle box and shuttle openings and engage the bobbin holding finger 20. This is termed the shuttle feeler. The other arm of the bell crank lever is connected by an adjustable link 35 with one end of a bell crank lever 36 pivoted on the extremity of the short arm of the lever 28. The other end of the bell crank lever extends into the slot 26 of the trigger 24. This bell crank lever 36 is provided with a stop 37 adapted to engage a projection 38 on the lever 28, limiting movement of the lever 36 in one direction and consequently the movement of the lever 33 in a corresponding direction. It will be noted in Figure 2 that the lever 33 occupies and oscillates in a horizontal plane, while the lever 36 occupies and oscillates in a vertical plane. A spring 39 is fixed at one end to the lever 28 and at the opposite end bears against a pin 40 carried by the lever 33, the function of this spring being to urge the shuttle feeler 34 toward the shuttle and therefore to raise the free extremity of the lever 36, thus normally holding the trigger 24 in elevated position.

The form of filling feeler shown in Figure 1 is adapted for use with bobbins. When the device is to be used on a loom 40 operating with cops the feeler finger 29 is replaced by a broad blunt-edged knife 29^a.

The operation of the device is extremely simple. On alternate picks as the lay beats forward, the shuttle in the box is brought 45 against the feeler device and the filling feeler 29 in effect enters the shuttle slot and strikes the filling on the bobbin or cop. The continued forward movement of the lay then carries the feeler with it, so that the lever 28 is oscillated. The bell crank lever 36 being vertically disposed oscillates with the lever 28 and its tip slides in the slot 26 toward the tip of the trigger without any 50 change of elevation, so that the trigger is not moved but is held up clear of the weft hammer. As long as there is plenty of filling on the bobbin or cop, the filling feeler is engaged by the filling before the shuttle feeler is engaged by the shuttle and the lay 55 movement is imparted directly to the lever 28, so that no relative movement occurs between the filling feeler and the shuttle feeler. When the filling has run out to the point where replenishment is necessary, the 60 filling yields and permits the feeler finger 65

29 to enter the slot 21 of the bobbin, so that the lay movement is not communicated to the lever 28 and the advancing lay brings the shuttle into contact with the shuttle feeler 34. In practice, the shuttle feeler spring 39 70 is much weaker than the filling feeler spring 31, so that the lever 28 remains stationary and only the lever 33 moves. This movement is communicated through the link 35 to the bell crank lever 36, the free end of 75 which swings down and depresses the point of the trigger until it is caught by the tooth 25 of the advancing weft hammer. The movement of the weft hammer or other suitable part of the loom is then communicated 80 through the trigger 24 and arm 23 to rock the shaft 17 and set in motion the weft replenishing mechanism. If the replenishing mechanism should fail to operate, the feeler will continue to rock the shaft 17 at 85 each alternate pick and set the replenishing mechanism in operation until a new bobbin or cop is placed in the shuttle. If the feeler is mounted on a loom which does not automatically replenish filling, the shaft 17 may 90 have connection to the loom stopping mechanism. The operation of the device with a cop spike is exactly the same as when a bobbin is used, except that there being no slot in the cop spike, the device is adjusted 95 to operate when the filling on the spike is exhausted to a predetermined thickness. The blunt edged knife 29^a is found more suitable than the comparatively pointed feeler 29. It will be understood that the 100 penetration of the feeler 29 into the bobbin slot, as shown in Figure 4, has been exaggerated to clearly show the relative movement of the two feelers.

Having thus described our invention, 105 what we claim is:—

1. In a feeler mechanism the combination with a filling replenishing actuating mechanism and a constantly oscillating loom part of a filling feeler, and a shuttle feeler movably mounted on the filling feeler, a trigger on the replenishing actuating mechanism and means mounted on the filling feeler connected between the shuttle feeler and trigger and operating in a plane perpendicular to 110 the plane of operation of the filling feeler whereby the trigger is unaffected by filling feeler movement, said means being operable by the shuttle feeler to move the trigger into the path of the oscillating loom part. 115

2. In a feeler mechanism, the combination with an oscillating loom part, and a filling replenishing actuating means, of a filling feeler oscillatable by movement of the filling, a shuttle feeler mounted on the filling 125 feeler and independently oscillatable in the same plane as the filling feeler, a trigger adapted to transmit motion from the oscillating loom part to the replenishing actuating means, and connection between the shut- 130

tle feeler and trigger mounted on the filling feeler and inoperative to move the trigger by filling feeler movement.

3. In a device according to claim 2, a 5 spring connected between the filling feeler and shuttle feeler and operative to normally maintain the trigger out of the path of the oscillating loom part.

4. In a device according to claim 2, a 10 spring urging the filling feeler toward the shuttle, and a weaker spring connecting the filling feeler and shuttle feeler urging the shuttle feeler toward a shuttle and normally holding the trigger out of the path of the 15 oscillating loom part, whereby the shuttle feeler may be moved by a shuttle to shift the trigger into the path of the oscillating loom part.

5. In a feeler mechanism, the combination 20 with an oscillating loom part and a filling replenishing actuating means, of a feeler oscillatable by movement of the filling, a spring urging the feeler toward the filling, a support for the feeler and a stop on the 25 feeler engageable with said support to limit feeler movement toward the filling, a shuttle feeler mounted on the filling feeler and independently oscillatable in the same plane as the filling feeler, a second spring weaker 30 than the first connecting the filling feeler and shuttle feeler and urging the shuttle feeler toward a shuttle, a trigger adapted to transmit motion from the oscillating loom part to the replenishing actuating means 35 normally held out of the path of the oscillating loom part by said second spring, and connection between the shuttle feeler and trigger mounted on the filling feeler and inoperative to move the trigger by filling

feeler movement, and a second stop on the 40 filling feeler engageable by the connection to the trigger to limit movement of the shuttle feeler toward the shuttle and the effect of the shuttle feeler spring upon the trigger. 45

6. In a feeler mechanism, a support, a lever mounted thereon forming a filling feeler, a bell crank lever mounted on one end of said lever and forming a shuttle feeler, a second bell crank lever mounted on the opposite end of said lever in a plane perpendicular to the first and a link connecting said bell crank lever. 50

7. In a device according to claim 6, a 55 spring fixed at one end to the support and bearing at the opposite end against the lever, a stop on the lever engaging the support and limiting spring actuated lever movement in one direction, a weaker spring mounted at one end on the lever and engaging at the opposite end with the first bell crank lever, and interengaging stops on the lever and second bell crank limiting spring actuated bell crank movement in one direction. 60 65

8. In a feeler mechanism, a support, a lever mounted thereon forming a filling feeler, a bell crank lever mounted on one end of said filling feeler and forming a shuttle feeler, a second bell crank lever on 70 the opposite end of said filling feeler and an adjustable link connecting said bell crank levers.

In witness whereof, we have hereunto set out hands.

WILLIAM H. BAKER.
CLARK E. CARTER.
